UNITED STATES PATENT OFFICE.

ARMINDA BEATRICE RUSH, OF NEW YORK, N. Y.

WINDOW-SHADE GUIDE.

No. 831,631.

Specification of Letters Patent.

Patented Sept. 25, 1906.

Application filed June 8, 1905. Serial No. 263,801.

To all whom it may concern:

Be it known that I, ARMINDA BEATRICE RUSH, a citizen of the United States, residing at New York, in the county of New York and State of New York, have invented a new and useful Improvement in Window-Shade Guides, of which the following is a specification.

This invention relates to an improved window-shade guide especially designed for guiding the shade upon the roller when the former is raised and causing it to wind easily and to hang perfectly straight in any position, even should the shade be fastened unevenly when first secured to the roller.

The objects of the invention are to provide a device that is exceedingly cheap as to cost, simple in construction, easy of application, and one in which the appearance of the window and shade will not be disfigured or impaired.

A further object is to provide a device that will catch the shade and prevent its being suddenly wound upon its roller, as often happens, by the sudden releasing of the roller-spring and one that will not damage the edges of the shade while being raised or lowered.

With these briefly-stated objects in view the invention also comprises certain details of construction and peculiar arrangement of parts, as will be fully described in the following specification and pointed out in the claim, reference being had to the drawings, in which—

Figure 1 is a perspective view showing the general application of my invention. Fig. 2 is an enlarged detail perspective view of the same. Figs. 3 and 4 show a slightly-modified construction; and Figs. 5, 6, and 7 show further modified forms of the guide.

As shown in Figs. 1 and 2 of the drawings, I construct the guide F of a single piece of wire, which is bent intermediate its ends at points F'. Each end is then extended rearwardly to a point F² and thence forwardly to a point F³, which provides an open loop F⁴, and finally backwardly, as shown at F⁵, the extreme ends being pointed to permit the guides being easily driven into the window-frame.

In Fig. 3 I show a slightly-different construction to that shown in Figs. 1 and 2 in that only one point G is provided instead of two, as shown in Fig. 2. In this construction the loops G⁴ are provided similar to the loops F⁴, and instead of extending both ends rearwardly and of an even length I converge them; as shown at G⁵, and make one end shorter than the other, the shorter end being wrapped one or more times around the longer end, as at G⁶, which securely fastens the ends together. The longer end may be pointed, as shown in Fig. 3, or threaded similar to a wood-screw, as at G⁷ in Fig. 4.

In Fig. 5 of the drawings I show a guide H, in which only one open guide-loop is produced, and this construction of guides is also formed of a single strand of wire which is bent intermediate its ends at a point H', and one end is extended backwardly upon the opposite end to a point H² and then bent forwardly to provide an open guide-loop H³, the extreme end being bent outwardly to form an eye, as shown at H⁴. The longer end of the wire is flattened to provide a point H⁵ to facilitate the guides being driven into the window-frame and also to prevent the guides turning after being secured in position.

The construction shown in Fig. 6 is somewhat similar to the construction shown in Fig. 5, the only difference being that I bend the wire centrally at I and extend each end in a substantially parallel direction to points I' to provide the open guide-loop I⁴, and from the point I' each member is bent back upon itself, as shown at I⁵, which portions I⁵ project some distance beyond the inner end of the open loop and have their extreme ends pointed. In Fig. 7 a similar construction to that shown in Fig. 6 is provided, only the ends I⁴ are bent under the parallel portions that form the loops instead of upon the sides.

From the foregoing it will be seen I provide a series of guides which are exceedingly simple in construction, and by reference to Fig. 1 of the drawings the location or position of the guide may be clearly understood, and a further detail description thereof is thought unnecessary.

Having thus fully described my invention,

what I claim as new, and desire to secure by Letters Patent, is—

A shade-guide formed of a single strand of wire bent upon itself to form a U-shape guide member opening outwardly, and having the ends of the portions forming the U-shape member bent backwardly to provide rounded edges to avoid injury to the shade, and one

end being extended past the inner end of the U-shape portion and its extreme end flattened for the purpose set forth.

ARMINDA BEATRICE RUSH.
